United States Patent Office

Des. 205,385
Patented July 26, 1966

205,385

WATER CRAFT

Walter Andersen, 1443 W. Birchlawn Place, Ottawa, Ill.

Filed Jan. 5, 1966, Ser. No. 475

Term of patent 14 years

(Cl. D71—1)

Fig. 1

Fig. 2

→ 9   → 8   → 7

Fig. 3

FIGURE 1 is a side view of one side of a water craft embodying my design, the side not shown being a mirror image of that shown;

FIGURE 2 is a top plan view thereof;

FIGURE 3 is a view of the bottom of the water craft;

FIGURE 4 is a front elevational view of the bow of the craft showing particularly the design of the steering mechanism;

FIGURE 5 is an elevational view of the stern;

FIGURE 6 is a top perspective view;

FIGURE 7 is a sectional view along the line 7-7 of FIGURE 2;

FIGURE 8 is a sectional view along the line 8-8 of FIGURE 2; and

FIGURE 9 is a sectional view along the line 9-9 of FIGURE 2.

I claim:

The ornamental design for a water craft, as shown and described.
